UNITED STATES PATENT OFFICE.

AUGUST MEYER, OF MOUNT PROSPECT, ILLINOIS.

DESIGN FOR A MATCH-SAFE.

44,379.

Specification for Design.

Patented July 22, 1913.

Application filed May 3, 1913. Serial No. 765,386. Term of patent 7 years.

To all whom it may concern:

Be it known that I, AUGUST MEYER, a citizen of the United States, residing at Mount Prospect, in the county of Cook and State of Illinois, have invented a new, original, and ornamental Design for a Match-Safe, of which the following is a specification, reference being had to the accompanying drawing, forming part thereof.

In the drawing, Figure 1 is an elevation of a match safe showing my new design. Fig. 2 is an edge view thereof. Fig. 3 is a top or plan view.

I claim:

The ornamental design for a match safe, as shown.

AUGUST MEYER.

Witnesses:

ALBERT HANSING,
A. T. MEYER.
